DELIVERY RECEPTACLE AND LOCKING MEANS

John Majors, Muskegon, Mich.

Application July 5, 1938, Serial No. 217,342

7 Claims. (Cl. 232—1)

This invention relates to an improved delivery receptacle and locking means, and the present application for patent shows and describes an improvement over my prior Patent No. 2,034,916 dated March 24, 1936.

One of the important objects of this invention is to provide a delivery receptacle with an improved locking means whereby the outer doors of said receptacle can be opened only at the will of the operator or at least under the control of the operator of the inner door.

Another important object of the invention is the provision of a safety delivery receptacle such as for milk and the like whereby the inner door is normally in a closed position, thereby preventing anyone opening the outer door, even an authorized person, from getting any access to the interior of the building in which the receptacle is placed or even obtaining a view of the interior of such building or room.

Still another important object of the invention is to provide a delivery receptacle and locking means for use with various commodities, particularly milk in bottles, groceries, and other products which may accordingly be delivered to a dwelling without in any way disturbing the occupants and also in such a manner that the delivered products will be secure against theft and protected from the elements.

Another and still further important object of the invention is to provide a delivery receptacle for milk or the like which is provided with a locking means such that the receptacle can be readily opened from the outside for the deposit of bottled milk or some other commodity, but which will be automatically locked from the outside after the closing of the outer door, thereby preventing any further access to the interior by unauthorized persons from the outside while, at the same time, readily permitting entrance from the inside door, and the convenient and ready withdrawal of the deposited commodities.

A still further object is to provide a simple yet efficient and sturdy type of lock which will automatically permit the alternate locking and unlocking of the outer door depending upon the operation of the inner door.

Other and further important objects of the invention will be apparent from the disclosures in the accompanying drawings and following specification.

The invention, in a preferred form, is shown in the drawings and hereinafter more fully described.

In the drawings:

Figure 1 is a vertical sectional view of the improved delivery receptacle and locking means of this invention, the locking means being shown inclosed in a case and both doors being shown as closed with the outer door locked.

Figure 2 is a view similar to Figure 1, but showing the outer door open.

Figure 3 is a front view of the special extra latching means developed for the latch of the outer door.

Figure 4 is an end view of the locking means, looking at the same from the outer side.

Figure 5 is a detail view, showing the interior of the lock construction and the cooperation of the parts thereof with the latching means of the outer door which is shown in closed position, but not locked.

Figure 6 is a view similar to Figure 5, showing the operation of the bar operated by the inner door in dotted lines and also showing the outer door in locked position.

Figure 7 is a detail view, parts being broken away, showing a slightly modified form of the invention.

Figure 8 is an inside view of the structure of Figure 7.

Figure 9 is a detail view showing the apparatus of Figure 8 in a different position.

Figure 10 shows another position of the apparatus of Figures 8 and 9.

Figure 11 is a detail showing the co-operating holes in the sliding plate and casing for passage therethrough of the detent.

As shown in the drawings:

The reference numeral 10 indicates generally the side walls of the improved delivery receptacle of this invention, the same generally comprising the casing of substantially rectangular form built into a wall 12 and in such a manner that the casing provides a passageway through the wall.

The receptacle 10 is provided with an outer door 14 having a handle 61 and being hinged at 16 to the casing 10 and an inner door 18 likewise hinged as at 20.

Mounted upon the inner face of one wall 10 of the receptacle itself is the improved locking element of this invention, the same comprising generally a casing 22 having positioned therein a spring-pressed detent 24, which detent has a projecting end 26 adapted to be forced through an opening 23 in the top of the casing 22 to engage with a keeper 28 on the outer door 14.

Also positioned in the casing 22 is a slid able plate 30 normally maintained in forward pos-

tion by means of a helical spring 32 as best shown in Figures 5 and 6.

Pivotedly mounted at 34 on the keeper plate 28 is a latch-operating element 36 which is adapted to be held in vertical position with one end normally down by means of a coil spring 38 (Figure 1).

When the outer door 14 is being closed, as best shown in Figure 2 the pivoting latch element or plate 36 contacts the outer end of the plate 30 and pushes it into the casing as the tension of the spring 38 is greater than the tension of the spring 32 attached to the plate 30, whereupon the pin 33 travels along the elongated slot 35. This pivoting latch element or plate 36 then strikes the upper part of the casing 22 and the spring 38 affixed to the latch element 36 allows the same to turn in an arc about the point 34. This resultant position is shown in Figure 6, whereby the detent 26 is allowed to move upwardly through the now aligned hole 31 in the plate 30, this being on account of the tension of the spring 40 attached to the detent 26. This upward movement of the detent 26 allows the end of same to move into an opening in the keeper 28 which is attached to the outer door 14, thereby securely locking the outer door in closed position. This, of course, occurs after a deposit of some commodities into the receptacle 10.

The inner door 18 is never locked against opening inasmuch as this is on the inside of the room or dwelling, but the same can be latched in closed position by means of an ordinary latch 42 and preferably is maintained in closed position by means of spring hinges 44.

When the inner door 18 is opened, a rod 46 which has been normally pushing against the inner face of the inner door as shown in Figure 2 is immediately retracted into the position shown in the dotted lines in Figure 6 by action of the helical spring 48, and this retracting of the rod 46 enables its cammed nose 50 to move rearwardly past a pivoted corresponding bar having a cam surface 52 as best shown in Figures 5 and 6.

This rearward motion of the rod 46 and its cammed end 50 will have no effect on the position of the detent 26, and the outer door 14 will still remain locked, thereby preventing access by anyone into the interior of the compartment while the housewife or other person is removing materials from the compartment.

However, upon closing the inner door 18, the rod 46 is immediately returned to its full line position as shown in Figure 5 on account of the pushing action of the inner face of the inner door there-against.

This action allows the cam 50 to move over the upper end of the bar having a cam surface 52 pushing the same downwardly into the position shown in dotted lines in Figure 6, it being understood that the detent 26 is bent rearwardly into a continuing part 56 as shown and that the bar having a cam surface 52 is pivotally mounted on the inner end of the continuation 56 of the detent 26. The detent element 26-56 and the bar having a cam surface 52 are held in position by means of a retaining plate 58 as shown in Figures 4, 5 and 6, and a coil spring 60 retains the bar having a cam surface 52 in position regardless of the action of the cam 50. Figure 5 shows the outer door in unlocked position.

In the modified form of the invention illustrated in Figures 7 to 10 inclusive, the outer

door 64 is provided simply with a pull handle 66, there being no locking or latching means associated with this handle, and the inner door 68 is provided with a simple latching element 70 operated by a handle 72.

Fastened upon the inner face of the outer door 64 is a catch 74 shaped, as shown, to contact with the upper end of the detent element 26 when this element is in its raised position as shown in Figures 9 and 10. This detent element is held in position in the lock casing 76 by means of a plate 78, and instead of the spring 40 of Figures 1 to 6, a helical spring 80 is provided which is behind the plate 78 and normally acts to impel the detent element 26 into raised position. Instead of the latching element 36 of Figures 1 to 6, a somewhat similar latching element in the form of a tumbler 82 is provided pivotally mounted on the locking lug 74 and normally impelled into the position of Figure 10 by means of the spring 84. The curved lower face of this element 82 rides over an upwardly curved extension 86 of the lock casing 76, and this upwardly curved extension is so shaped that the door 64 is normally held closed by means of the contact between the lower curved face of the element 82 and this extension 86 as best shown in Figures 8 and 9. A sufficient pull on the knob 66 will, however, release the door 64.

The spring 84 is of such tension that a closing movement of the door, no matter how fast, will still allow the tumbler element 82 to contact the outer end of the slide 30 and push it into retracted position as shown in Figures 9 and 10, thereby allowing the upper end of the detent 26 to pass through the hole in the slide 30 and assume the position shown in Figures 9 and 10 whereby when the door 64 is closed, it will immediately become locked as shown in Figure 9, inasmuch as the cammed-face nose of the lug 74 will ride over the correspondingly cammed-face end of the detent 26, pushing it downward slightly against the tension of the spring 80 until such time as the end of the lug 74 has passed beyond the detent 26 whereupon the spring 80 will force it upwardly into the locking position of Figure 9.

The lock casing 76 of Figures 7 to 10 inclusive has slots 88 in its flanges whereby its position may be somewhat varied with regard to the supporting bolts 90 and with regard to the inside wall 92 of the receptacle and, of course, correspondingly with regard to the door 64 and the locking lug 74 whereby suitable relative adjustment of these parts may be readily and simply provided.

The extension 46a of the rod 46 and the cam 50 is tapered as shown in Figures 8 and 9, and has a further extension 94 mounted thereon by means of a removable pin 96 whereby this extension 94 may be readily removed and replaced by one either longer or shorter, thereby adapting the locking device for housings 92 of different widths or dimensions. The outer end of the rod 94 is held in one or more supporting brackets 98 as shown.

It will be seen that herein is provided an absolutely safe, yet simple and efficient delivery receptacle which will enable the housewife to be assured that milk, groceries, etc., will be delivered, and regardless of the time of delivery, will be safe against tampering or theft, it being further understood that the latch 42 on the inner door will prevent any pushing of this door open from the outside even though the outer

door be opened by some unauthorized person before the arrival of the milk man or other delivery person. Obviously, the handle 66 on the outer door is merely for the purpose of operating the same.

Then again, after the material has been deposited in the receptacle, the outer door is automatically locked and is only released after the housewife or some other person on the inside of the building opens the inner door, and even then, the outer door cannot be opened until the inner door has been again closed, thereby guarding against any unauthorized access by a sneak thief or the like who might, knowing the conditions, otherwise wait outside the outer door until hearing the inner door open and then quickly open the outer door in time to either snatch some of the contents or perhaps do bodily harm to the person inside the building.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. A locking means for two cooperating doors, comprising a casing, a detent for one door mounted for vertical sliding movement in the casing, a spring for normally impelling the detent upwardly, a bar having a cam surface pivotally mounted on the detent, and means for lowering the detent comprising a cooperating cammed rod slidably mounted in the casing for operating contact with the other door.

2. A locking means for two cooperating doors, comprising a casing, a detent for one door mounted for vertical sliding movement in the casing, a spring for normally impelling the detent upwardly, a bar having a cam surface pivotally mounted on the detent, and means for lowering the detent comprising a cooperating cammed rod slidably mounted in the casing for operating contact with the other door, said cammed rod projecting beyond the lock casing, and spring means for normally forcing said cammed rod into a position beyond the normal closed position of the second door, and a plate slidably mounted in the casing adjacent the upper end of the detent, said plate having an opening therein for passage of the nose of the detent therethrough when the detent is not in lowered position.

3. A locking means for two cooperating doors, comprising a casing, a detent for one door mounted for vertical sliding movement in the casing, a spring for normally impelling the detent upwardly, a bar having a cam surface pivotally mounted on the detent, and means for lowering the detent comprising a cooperating cammed rod slidably mounted in the casing for operating contact with the other door, said cammed rod projecting beyond the lock casing, and spring means for normally forcing said cammed rod into a position beyond the normal closed position of the second door, and a plate slidably mounted in the casing adjacent the upper end of the detent, said plate having an opening therein for passage of the nose of the detent therethrough, and a spring connected to the plate constantly impelling the same into projected position.

4. A safety delivery receptacle comprising a housing, inner and outer doors, locking means

for the outer door comprising a keeper mounted on the inner face of the outer door, a lock casing mounted on the inner face of the wall of the receptacle, and a slidable detent positioned in the lock casing adapted to cooperate with the keeper on the outer door, a pivoting plate on the keeper and a slidable plate in the lock casing adjacent the pivoting plate and mounted for cooperation therewith, the slidable plate having an opening therein for upward passage of the detent therethrough upon rearward movement of the slidable plate.

5. A safety delivery receptacle comprising a housing, inner and outer doors, locking means for the outer door comprising a keeper mounted on the inner face of the outer door, a lock casing mounted on the inner face of the wall of the receptacle, and a slidable L shaped detent positioned in the lock casing adapted to cooperate with the keeper on the outer door, a pivoting plate on the keeper and a slidable plate in the lock casing adjacent the pivoting plate and mounted for cooperation therewith, the slidable plate having an opening therein for upward passage of the detent therethrough upon rearward movement of the slidable plate when contacted by the pivoting plate, and spring means on both the slidable and pivoting plates, the spring on the pivoting plate being of a greater tension than the spring on the slidable plate, together with a spring attached to the detent for normally forcing the same upwardly through the opening in the slidable plate and into the keeper on the outer door upon closing of the outer door, and a bar having a cam surface pivotally mounted on the inner end of the detent, and means abutting the inner door co-acting with said bar for lowering the detent upon closing of the inner door.

6. A safety delivery receptacle comprising a housing, inner and outer doors, locking means for the outer door comprising a keeper mounted on the inner face of the outer door, a lock casing mounted on the inner face of the wall of the receptacle, and a slidable L shaped detent positioned in the lock casing adapted to cooperate with the keeper on the outer door, a pivoting plate on the keeper and a slidable plate in the lock casing adjacent the pivoting plate and mounted for cooperation therewith, the slidable plate having an opening therein for upward passage of the detent therethrough upon rearward movement of the slidable plate when contacted by the pivoting plate, and spring means on both the slidable and pivoting plates, the spring on the pivoting plate being of a greater tension than the spring on the slidable plate, together with a spring attached to the detent for normally forcing the same upwardly through the opening in the slidable plate and into the keeper on the outer door upon closing of the outer door, and a bar having a cam surface pivotally mounted on the inner end of the detent and means abutting the inner door for lowering the detent upon closing of the inner door, said means comprising a rod having a cammed nose slidably mounted in the lock casing, whereby closing of the door will actuate the bar having a cam surface.

7. A safety delivery receptacle comprising a housing, inner and outer doors, locking means for the outer door comprising a keeper mounted on the inner face of the outer door, a lock mounted on the inner face of the wall of the receptacle, and a slidable L shaped detent posi-

tioned in the lock casing adapted to cooperate with the keeper on the outer door, a pivoting plate on the keeper and a slidable plate in the lock casing adjacent the pivoting plate and mounted for cooperation therewith, the slidable plate having an opening therein for upward passage of the detent therethrough upon rearward movement of the slidable plate when contacted by the pivoting plate, and spring means on both the slidable and pivoting plates, the spring on the pivoting plate being of a greater tension than the spring on the slidable plate, together with a spring attached to the detent for normally forcing the same upwardly through the opening 15 in the slidable plate and into the keeper on the

outer door upon closing of the outer door, and a bar having a cam surface pivotally mounted on the inner end of the detent, a spring for normally maintaining the bar in vertical position and means abutting the inner door for lowering the detent upon closing of the inner door, said means comprising a rod having a cammed nose 5 slidably mounted in the lock casing, and a spring connected to the rod for normally impelling the same into projected position against the inner 10 face of the inner door, whereby a closing of the inner door actuates the cammed nose of the rod against the cam surface of the bar pivotally mounted on the inner end of the detent.

JOHN MAJORS. 15
